ABSTRACT OF THE DISCLOSURE

The deployment of a survival kit for flight personnel is illustrated in general in U.S. Pat. No. 3,182,928, granted to John A. Gaylord on May 11, 1965. There are various types of emergency release handles whereby the emergency kit can be deployed, for instance, in the manner shown in FIG. 11 of the aforementioned patent.

The herein deployment device has a selector for selecting either manual or automatic deployment of the kit. In the case of automatic deployment the release mechanism is operated through a detonator actuated piston motor, which is in the form of a cartridge with a detonator cap in one end which detonates a slow-burning pyrotechnic charge of predetermined characteristics to delay for a predetermined period the igniting of the main charge, which main charge is also comparatively slow-burning so that the gases developed by combustion expel a piston from the cartridge, and the piston operates the releasing mechanism. A trigger device with a firing pin is in registry with the detonator cap in the end of the cartridge, and is cocked for firing and is actuated by a device connected to the seat of the crewman so that when the crewman separates from the seat the firing pin is actuated. In another form the firing pin assembly is actuated by a device connected to the parachute so that when the parachute opens the pull exerted by the parachute releases the firing pin and then the piston motor, after a predetermined time, operates the deployment mechanism.

Background of the invention

It is essential that the deployment of the survival equipment be initiated with sufficient delay after the separation of the air crewman from his seat, or after the opening of his parachute, to prevent entanglement of the survival kit with the parachute shrouds or other supporting lines. Therefore it is essential that whenever the deployment of the survival kit is actuated automatically either by the separation from the seat, or by the opening of the parachute, that the automatic actuation of the releasing or deployment device be delayed for a predetermined period. It is also essential that the crewman have the option for controlling the deployment manually whenever that may be advantageous and that such selection may be made quickly by merely turning the switchlike button or handle.

In the present invention the delaying action is accomplished by a piston motor wherein the piston is moved by the burning of an explosive charge, which, however, is not ignited until a slower burning explosive charge has been burned for a predetermined period of time, for instance, three seconds. The slower burning charge is ignited by a primer, which latter is fired by a firing pin. A mechanism to operate the firing pin is adapted to be cocked and to be released for firing either by a device connected to the seat of the crewman and pulled when the crewman and the kit are separated from the seat, or by a pull line connected to the parachute shroud or line to be operated by the pull of the parachute when it is opened. In this manner the entangling of the kit or its lines with the shroud lines of the parachute or other supports of the crewman

2

is entirely obviated because not only automatic deployment after predetermined delay is accomplished, but the crewman is also afforded the choice of simple manual operation.

Description of figures

5 FIG. 1 is a side view of the deployment device mounted on the right hand side of the kit.

10 FIG. 2 is a side view of the deployment device with the cover removed and certain parts in section.

15 FIG. 3 is a side view of a modified form of the device with the covers removed and parts in section.

20 FIG. 4 is a sectional view of the piston motor and the firing pin, the section being taken substantially on lines 4—4 of FIG. 3.

25 FIG. 5 is a fragmental plan view of the part of the mechanism for release by parachute line and also the connecting lines for actuating the release mechanism viewing substantially in the direction of the arrows 5—5 of FIG. 6.

30 FIG. 6 is a partly sectional view of the connecting device to the parachute line for actuating the trigger and the firing pin.

35 FIG. 7 is a sectional perspective view of the firing mechanism.

40 FIG. 8 is a sectional perspective view of the firing mechanism cocked ready for firing.

Detailed description

30 The invention is applied to survival equipment such as a survival kit which has a container casing 1 and a lid 2 which is held in place by releasable coacting locking means of the type shown in FIGS. 1, 2 and 3 of the aforementioned patent and described therein. One of the functions of the herein deployment device is to pull the actuating line 3 which releases the interlocking mechanism 4 thereby to release the lid 2 from the casing 1 and deploy the parts of the survival kit substantially in the manner shown in FIG. 2 of said patent.

40 The deployment device herein has a handle or cartridge actuated line pulling and actuating mechanism 6 for pulling the line or cable 3 for the deployment of the kit, and a selector and firing device 7 which selectively fires the charge in the cartridge actuated mechanism 6 or permits the actuation of mechanism 6 manually by a handle 8.

45 The line pulling or actuating mechanism 6 includes a housing 9 covered by a cover plate 11. The housing 9 has therein guide rails 12 between which is slideably held a slide block 13, which latter is shorter than the rails 12 so that there is a space 14 provided between the slide block 13 and the housing end 16 to permit the reciprocation of the sliding block 13. The line or cable 3 extends through the other end wall 17 of the housing 9 and is suitably connected to the slide block 13, for instance by 50 the ball and socket connection 18. For deployment of the survival kit a slide block 13 is moved toward the housing end wall 16 thereby to pull the actuating line 3 to release the interlocking device 4 in the manner described in said U.S. Pat. No. 3,182,928.

55 A slide locking bar 19 is guided in a groove 21 in the bottom of the housing 9 and extends at right angles and across the rails 12 and has a slide locking finger 22. The lower edge of the slide block 13 has a locking notch 23. A suitable spring 24 anchored on the bottom of the housing 9 bears against a projection 26 on the side of the slide locking bar 19 so as to urge the slide locking bar 19 toward the handle 8, thereby to urge the slide locking finger 22 into the locking notch 23 for holding the slide locking block 13 in the releasing position. The locking notch 23 is spaced from the end 26 of the slide block 13 at about the same distance as the spacing between the housing end wall 16 and the slide block end 26, so that the notch 23 is

registering with the slide locking finger 22 in the retracted position the slide lock 13.

For the manual release operation the handle 8 has a projecting flange 27 insertable through a top opening 28 into the housing 9. The projection extends down to the pulling end 29 of the slide block 13 and has a roller 31 bearing against said pulling end 29. On an edge of the handle flange 27 is a socket 32 which bears against a roller 33 on a pin 34 in the housing 9 spaced above the roller 31. A hook 36, extended from the flange 27, spaced from the socket 32, bears against a pivot roller 37 on a pivot pin 38 in the housing 9, so that when the handle 8 is pulled out of the housing 9, the roller 31 is pushed against the block end 29 as the handle flange 27 pivots around the pivot roller 33. The outline of the flange is such that as it pivots around the pivot roller 33 the socket 32 clears the roller 33. The space between the roller 33 and the slide locking bar 19 is sufficient to permit the withdrawal of the flange 27 from the housing 9 after the slide block 13 was pushed in proximity to the housing end 16. The upper end of the slide locking bar 19 bears against a projection 39 on the underside of the flange 27 between the socket 32 and the hook 36 so that the action of the spring 24 yieldably releases slide block 13.

For automatic operation a lug 41 projects from the slide block 13 past the lower rail 12 into the lower half of the housing 9. The lower half of the housing 9 has spaced sockets 42 into which can be placed a cartridge 43, which is held in place by the cover plate 11, which latter is suitably secured, such as by screws, to the housing 9. A piston 44 projects from the end of the cartridge 43 and bears against the lug 41 so that when the piston 44 is propelled by the products of combustion in the cartridge 43 it pushes the block 13 toward the housing under wall 16 and thereby pulls actuating line 3.

The cartridge 43 is shown in detail in FIG. 4. The cartridge has a casing 46 through an end 47 of which reciprocates the piston 44. In the other end of the cartridge casing 46 is a detonator cap 48 which starts the burning of the slow-burning detonator charge 49. The time of the burning of the detonator charge 49 is predetermined, for instance for present release operations, about three seconds. Upon the detonation of the detonator charge 49 the main charge 51 behind the piston 44 is ignited. The main charge 51 is also comparatively slow burning so as to exert gradual force on the piston 44 and move the block 13 gradually to pull the pull line gradually.

The cartridge 43 is fired by a firing pin device 52 which latter is actuated by the pull exerted on the firing line 53 by the automatic firing device 7. The automatic firing device as shown in FIG. 2 includes a separate housing 61 with a cover plate 62 suitably fastened on a housing 61, for instance, by screws. In the housing is a slider 63 to which the firing line 53 is connected. The slider 63 moves in a suitable groove 64 in the bottom of the housing 61. The groove 64 is longer than the slider 63 so as to allow the reciprocation of the slider 63. In the lower side of the slider 63 is a notch 66 for engagement by a finger 67 on an actuating cam 68. The actuating disc cam 68 is positioned in a recess 69 and in the bottom of the housing 61 which is so shaped as to generally accommodate the cam 68. The bottom of the housing 61 is open to permit insertion and withdrawal of the disc cam 68. In the edge of the actuating cam 68 is a socket 71 loosely fitting over a roller 72. The actuating cam 68 has an arcuate edge 73 curving into a substantially flat top edge between the top of the arcuate edge 73 and the finger 67. The other edge 76, below the socket 71, fits against the adjacent wall 77 of the recess 69. From a side of the actuating cam 68 projects a stub shaft 79, spaced from the cam base 78. On the stub shaft 79 is a resiliently yieldable reel 81 urged normally to be wound around the stub shaft 79. A connecting line or strap 82 is wound upon the reel 81 and is provided with means thereon for detachable connection to the seat on which the crewman is seated.

When the crewman is separated from his seat the line 82 unrolls to allow sufficient clearance for the crewman from the aircraft or from the ejection seat, and after it is unwound entirely, then it pulls the cam actuator 68 around its abutting edge 76 as a fulcrum. The wall 83 of the recess 69 adjacent the arcuate edge 73 of the cam 68 is so shaped that the arcuate edge 73 of the cam 68 clears the adjacent sides of the recess. The roller 72 holds the finger 67 in the notch 66 of the slider 63. The notch 66 is longer than the width of the finger 67. As the cam 68 is pulled out of the recess 69 and turns about its abutting edge 76, it moves the slider 63 and thereby pulls the line 53 for cocking and firing the firing pin device 52 in a manner hereinafter described.

15 The selector device is for the purpose of changing the position of the roller 72 so as to permit the withdrawal of the cam 68 without pulling the slider 63 to a sufficient distance to actuate the firing pin device 52. For this purpose the roller 72 is journaled in a selector bar 84. The side of the selector bar 84 at the roller 72 has a recess 85 therein to accommodate the neck 86 of the cam 68. The recess 85 is considerably longer than the width of the neck 86 so as to permit the movement of the selector bar 84 between guide grooves 87 and 88 in the housing 61. When the selector bar 84 is pushed left viewing FIG. 2 into the groove 88, that shifts the position of the roller 72 to substantially under the finger 67 so that the cam 68 may drop out after very slight sliding of the slider 63 and does not pull the line 53 sufficiently far to cock and fire the firing pin device 52.

30 The selector bar 84 is shifted by a lever 89 which is pivoted substantially intermediate its ends on a pivot shaft 91. The lever 89 is positioned in an extension 92 of the housing 61 located along the outside of the end wall 16 of the housing 9. At the top of the extension 92 is an elongated longitudinal slot 93 in which slot is movable an arm 94 extended from the lever 89. An arcuate head 96 on the top end of the lever 89 covers the top of the housing extension 92.

40 In order to switch the device for manual operation, the arm 94 is pushed down from the full line position to the broken line position shown in FIG. 2, whereupon the lower end of the lever 89 pushes the selector bar 84 into the groove 88 so as to shift the roller 72 to about under the finger 67 and thereby permit the falling out of the cam 68 without actuating the firing pin. For automatic operation the arm 94 is pulled up into the full line position shown in FIG. 2, which compels the movement of the finger 67 to a substantial distance before the cam 68 can separate from the recess 69 and thus automatically actuate the firing pin device 52.

45 The firing pin device 52, shown in detail in FIGS. 3, 4, 7 and 8, includes a cocking stem 97 reciprocating in a cocking tube 98. The cocking line 53 is connected by a ball and socket connection 99 to the cocking stem 97. A cap 101 screwed on the outer end of the cocking tube 98 clamps the head 102 of a line guide tube 103 in fixed position. A coil spring 104 between the head 102 and the cocking stem 97 normally holds the cocking stem 97 against a seat 106 in the tube 98 in an initial position as shown in FIG. 7.

50 Beyond the seat 106 is a passage 107 of smaller diameter than the diameter of the cocking stem 97 for slidably receiving a firing pin 108. In an enlarged passage 109 beyond the passage 107 is a cocking spring 111 between the shoulder of the enlarged passage 107 and a collar 112 on the firing pin 108. The firing tip 113 of the firing pin 108 is of reduced diameter to fit the detonator cap 48.

55 A reduced extension 14 on the end of the cocking stem 97 extends into a socket 116 in the adjacent end of the firing pin 108. A plurality of balls 117 are movable through holes 118 in the sides of the socket 116. A reduced neck 119 of the cocking stem extension 114 is 60 in registry with the holes 118 to receive the balls 117

thereby to interlock the locking stem and the firing pin, as shown in FIG. 7, in the smaller passage 107.

When the cocking line 53 is pulled to a sufficient extent, it pulls the cocking stem 97 from the initial position shown in FIG. 7 to the cocking position shown in FIG. 8, thereby compressing the cocking spring 111. When the holes 118 of the firing pin socket 116 pass beyond the stem seat 106, the end of the stem extension 119 pushes the balls 117 out of the holes 118 thereby disconnecting the cocking stem 97 from the firing pin 108, whereupon the cocked spring 111 snaps the firing pin tip 113 against the detonator cap 48 and fires the charges in the cartridge 43.

A detent is provided to hold the firing pin fixed, as shown in FIGS. 3 and 4. The firing end of the tube 98 has a flange 121 which is held in place on a detent boss 122 of the release housing 6 by a cap 123, in axial registry with the sockets 42 for the cartridge 43. The detent boss 122 has a transverse detent recess 124 at right angles to a guide passage 126 for the firing pin 108. A detent button 127 in the detent recess 124 extends across the guide passage 126. The detent button 127 has a hole 128 therethrough in registry with the guide passage 126. A detent 129 in the inside wall of the hole 128 fits into a socket 131 in the firing pin 108 to prevent moving the firing pin 108. A detent spring 132 between the bottom of the detent recess 124 and the inner end of the detent button 127 urges the button 127 outwardly so as to hold the detent 129 in the detent socket 131.

Before the cartridge 43 is inserted in the cartridge sockets 42, the firing pin device is set by pushing the button 127 into its recess 124 so as to free the firing pin 108, then a suitable tool is inserted into the guide passage 126 and the firing pin 108 is pushed until its socket 116 pushes the cocking stem 97 to about the position shown in FIG. 8, past the seat 106. The spring 104 pushes the reduced end 114 of the stem 97 into the end socket 116, so that when the tool is withdrawn the spring 104 pushes the stem 97 and the firing pin 108 into the interlocked initial position shown in FIG. 7, wherein the pin socket 131 is spaced from the detent 129. Thereafter the cartridge 43 is inserted and the device is ready for operation.

The modified form of the cocking line pulling and actuating mechanism 141, shown in FIGS. 3, 5 and 6, is primarily for actuation by a suspending line, such as parachute webbing, pulling on suspension line 142 through a device shown in FIG. 6.

In this form a sliding block 143 is guided in a pocket 144 in a housing 145. A lever 146 is pivoted on the sliding block 143. The cocking line 53 is connected to the upper end of the lever 146. To the lower end of the lever 146 is connected a pull line 147, leading from a line pulling device 148. When the sliding block 143 is fixed then the pulling of the pull line 147 turns the lever 146 in clockwise direction viewing FIG. 6, thereby pulling the cocking line 53 to operate the firing pin device 52.

The pocket 144 is open at one end and a spring 149 yieldably holds the sliding block 143 in the pocket 144. The sliding block 143 is held fixed by a pawl 151 fulcrumed on a pivot 152 in the housing 145 spaced from the sliding block 143. The pawl 151 fits in a cut away corner 153 of the block 143 to hold the block 143 stationary. When the pawl 151 is withdrawn from the cut away corner 153, the pulling of the pull line 147 moves the sliding block 143 against the spring 149 and thus the pull on line 53 is minimal and not sufficient to actuate the firing pin device 52.

The pawl 151 is shifted from automatic to manual operation by the lever 89 heretofore described, but the lower end of the lever 89 is pivotally connected to the pawl 151 by a link 154. The pawl 151 is shaped like a hook and the link 154 is pivoted in the corner or crook of the hook so that when the link 154 is pushed by the lever 89 into the position shown in broken lines in FIG. 3, then

the pawl 151 is lifted out of the cut away corner 153 and the block 143 is released for the manual operation.

The pull line 147 is extended through a tube 156 to the pulling device 148, as shown in FIG. 6.

The entire assembly of the pulling device 148 is enclosed in a sleeve 158 which is detachably held by a pawl 159 engaging a groove 161 near the base 162 of the sleeve 158. The pawl 161 is pivoted on a bracket 163 and a cable 164 is connected to its lower end. The cable 164 extends to the front of the kit casing 1 and connects to an end of a pivoted lever 165. By depressing the free end 166 of the pivoted lever 165 the cable 164 turns the pawl 159 out of the groove 161, thereby allowing the removal of the pulling device 148 from the kit casing 1.

The pulling device includes a pulling bar 157. The riser line 142 is connected to the pulling bar by a ball and socket joint. An outer slide cylinder 168 is connected to the bar 157 by a cross pin 169, which latter moves in elongated slots 171 in the sides of an inner slide cylinder 172. The inner slide cylinder 172 has suitable ball pockets 173 in its sides to accommodate balls 174 which are engageable with a reduced neck 176 in the upper end of a pulling stem 177 suitably connected to pull line 147. The outer slide cylinder 168 has an enlarged annulus recess 178 near its lower end as shown in FIG. 6. The pulling stem 177 is guided in plug 179 secured in the bracket 163. The inner slide cylinder 172 has a flange 181 on its top and a coil spring 182 between the flange 181 and the top of the outer slide cylinder 168 pushes the latter normally against the top of the plug 179 so that the annular recess 178 registers with the balls 174 and permits the balls 174 to be disengaged from the reduced neck 176.

The pulling bar 157 is guided in a flanged bushing 183, the flange 184 of which rests on the top of the sleeve 158 and is held there by a cap 185 threaded on the sleeve 158. A coil spring 186 between the flanges 184 and 181 is stronger than the coil spring 182 and presses the inner slide cylinder 172 also against the top of the plug 179. The ball sockets 173 are spaced from the lower end of the inner slide cylinder 172 the same distance as the distance of the annular recess 178 from the lower end of the outer slide cylinder 168 so that the pulling stem 177 is disengaged from the inner slide cylinder 172.

When the sleeve 148 is disconnected from the pawls 161 it can be pulled off the plug 179 without pulling the line pulling stem 177. But when the riser line 142 is pulled, it pulls the pulling bar 157 which through the cross pin 169 pulls the outer slide cylinder 168, and as the cross pin 169 slides in the slots 171 the annular recess 178 is pulled past the balls 174 and the outer slide cylinder 168 pushes the balls 174 against the reduced neck 176. As the cross pin 169 reaches the upper ends of the slots 171, the inner slide cylinder 172 is moved together with the pulling bar and pulls the pulling stem 177 which in turn pulls the pull line 147 to actuate the lever 146 as heretofore described.

The connection between the riser line 142 and the pulling bar 157 is in the form of a ball 187 in a bayonet socket 188 open to one side of the bar 157 so spaced from the top of the bar 157 that as the deployment device is actuated the ball 187 and the socket 188 clear the bushing flange 184 and thus the ball 187 is allowed to escape from the socket 188 and thereby frees the pulling device 148 for dropping away with the kit.

The pawl 159 is pulled out of the groove 161 during deployment by a pawl release line 189, shown in FIG. 6, which line 189 is suitably pulled simultaneously with the pulling of the actuating line 3, FIG. 3.

We claim:

1. In a deployment device for deploying a hung article, a mechanism for deploying the article, an actuating line to operate the deploying mechanism, a device to operate the actuating line including

a casing,

a sliding element slidably in the casing and con-

- nected to said actuating line thereby to pull said actuating line whenever the sliding element is moved,
- plunger means in said casing bearing against said sliding element for moving the same,
- pressure applying mean for applying pressure to said plunger element for moving said sliding element,
- means for hanging said article, and
- means connected between said pressure applying means and said hanging means for operating said pressure applying means whenever said article is dropped and hung on said hanging means.
2. The deployment device defined in claim 1 and a manipulable device for moving said sliding element thereby to pull said actuating line,
- selecting means to selectively render said pressure applying means inoperative for permitting manual operation.
3. The deployment device defined in claim 1 wherein said pressure applying means include a cartridge, said plunger being reciprocable in said cartridge,
- explosive charge in said cartridge for applying pressure against said plunger for moving said sliding element,
- a trigger and firing device connected to said operating means between the pressure applying means and said hanging means for firing said explosive charge after a predetermined period subsequent to the dropping and hanging of said article.
4. The deployment device defined in claim 3 and means to delay the burning of said explosive charge for a predetermined period after said firing.
5. The deployment device defined in claim 3 and said explosive charge in said cartridge including a main charge for pushing said plunger, and an initial slow-burning pyrotechnic charge for detonating said main charge.
6. The deployment device defined in claim 5 and said main charge being also comparatively slow-burning thereby gradually to move said plunger out of said cartridge.
7. The deployment device defined in claim 3 and said trigger and firing mechanism including a firing pin in registry with the firing end of said cartridge,
- a coil spring urging said firing pin towards said cartridge,
- a spring urged pulling element for cocking said firing pin by pulling said pin against said coil spring thereby compressing said coil spring,
- pulling means connecting said pulling element to said operating means whereby said operating means pulls said pulling element for cocking said firing pin whenever said kit is dropped and hung on said hanging means, and
- releasable connecting means between said pulling element and said firing pin disengageable after a predetermined travel when said firing pin is cocked, thereby to release said firing pin for firing said cartridge.
8. The deployment device defined in claim 7 and releasable safety locking means to lock said firing pin in fired position after each firing.
9. The deployment device defined in claim 2 and said manipulable device including a handle,
- an extension of the handle bearing against said sliding element, and
- separable means to pivotally hold said handle on said casing in position to move said sliding element for pulling said actuating line whenever the handle is turned about said pivotal means.
10. The deployment device defined in claim 9 and said handle pivoting means being releasable after a predetermined turn of the handle for pulling the actuating line, thereby to separate said handle from

- said casing after said deploying mechanism had been actuated.
11. The deployment device defined in claim 2 wherein said selecting means include,
- a lever pivoted between its ends,
- a pivoted link extended from the end of the lever adjacent said connecting means,
- a pulling line between said connecting means and said pressure applying means for operating said pressure applying means,
- an element in said connecting means for pulling said pulling line for operating said pressure applying means, and
- means operated by said link selectively to connect said connecting element for pulling said pull line or for limiting the pulling of said pull line to a lesser distance than necessary for operating said pressure applying means.
12. In a deployment device for deploying a hung survival kit, the combination with a deployment mechanism and an actuating line for actuating said deployment mechanism,
- an operating line suspended so as to be pulled when the article is dropped and is hung on said operating line, a casing on said kit,
- an element in the casing connected to said operating line to be moved thereby whenever said operating line is pulled,
- a sliding member in said casing,
- selecting means to selectively hold said element for sliding said sliding member beyond a predetermined distance for pulling said actuating line sufficiently far for automatically actuating said deployment mechanism or for limiting the sliding of said sliding member to less than said predetermined distance thereby to prevent automatic actuation of said deployment mechanism when said operating line is suspended and said article is dropped,
- connecting means between said element and said sliding member and said actuating line to pull said actuating line whenever said element is pulled by said operating line while said selecting means is set for automatic actuation,
- a manual device for actuating said deployment mechanism at will, and
- manipulable selector device on said casing to shift said selecting means for automatic and manual actuation.
13. In a deployment device defined in claim 12, wherein said element connected to said operating line includes a reel, said operating line being wound on said reel, said casing having a recess around said reel,
- a cam plate rotatably supporting said reel and being movable out of said recess about the axis of rotation of said reel by said operating line after the entire operating line is played out,
- a finger on said cam plate engageable with said sliding member for sliding said sliding member as said cam plate is rotated and withdrawn from said recess,
- said selecting means including a holding member engaging said cam plate to hold said finger in operative relation with said sliding member,
- said holding member being shiftable by said manipulable selective device partially out of engagement from said cam plate thereby to free said finger from said sliding member to permit withdrawal of said cam plate from said recess without sliding said sliding member sufficiently to actuate said deployment mechanism.
14. In a deployment device defined in claim 13, and said cam plate having a recess in its edge below said finger,
- said selecting means including a shifting link,
- said holding member extending from said shifting link into said recess in said cam plate,

a selecting lever pivoted in said casing, and being accessible for manipulation at one end thereof, its other end being connected to said link for shifting said holding member into and out of said recess in said cam plate respectively for automatic or manual actuation.

15. The deployment device defined in claim 12, wherein said element connected to said operating line includes, an actuating lever pivoted on said sliding member, one end of said lever being connected to said operating line, the other end of said lever being connected to said actuating line, a selector lever pivoted in said casing, one end of said lever being accessible for manipulation, a shifting link connected to the other end of the lever, 15 an obstruction member pivoted on said casing and connected to said link in position to engage said sliding member thereby to obstruct movement of said sliding member whereby said obstructed sliding member forms a fixed fulcrum for said actuating lever when pulled by said operating line, and causes the pulling of said actuating line, said shifting link being shiftable by said selecting lever to withdraw said obstruction member from said sliding member, whereby the pulling of said actuating line by said operating line is prevented, and 25 resiliently yieldable means to urge said sliding member in obstructed position relatively to said obstruction member.

16. The invention defined in claim 12, and 30 said operating line extending through said kit, means to suspend said operating line including, a tubular casing, 35 releasable means to detachably hold said tubular casing on said kit, manipulable means to release said releasable means, means operated together with the actuation of 40 said deployment mechanism to release said releasable means thereby to free said tubular casing from said kit, a pulling stem on the end of the operating line, a guide on said kit to guide said pulling stem within said tubular casing, a reduced neck on said stem, 45 interlocking balls in said neck, a pulling bar in said tubular casing, an inner sleeve around said pulling bar having apertures therein for interlocking with said balls, an outer sleeve around said inner sleeve, 50 resilient means to urge said outer sleeve into an initial position toward said guide, said outer sleeve having a releasing recess therein normally in registry with said balls thereby to release said pulling bar from said pulling stem, connecting means between said pulling bar and 55 said outer sleeve and said inner sleeve for pull-

5

ing said outer sleeve thereby to push said balls into engagement with said pulling stem neck and then to pull said inner sleeve and said pulling stem together to pull the operating line when said pulling bar is pulled,

means to suspend said pulling bar so as to pull said pulling bar whenever said kit is dropped and suspended.

17. The invention defined in claim 12 and said connecting means including, a second casing,

a sliding element slideable in the second casing and connected to said actuating line thereby to pull said actuating line whenever the sliding element is moved, means in said second casing bearing against said sliding element for moving said sliding element in said second casing, pressure actuated means for applying pressure to said moving means, and means interconnected between said pressure applying means and said sliding member for operating said pressure applying means whenever said sliding member is pulled beyond said predetermined distance.

18. The invention defined in claim 17, and said pressure applying means including, a reciprocating plunger bearing against said sliding element, a cartridge containing said plunger, explosive charge in said cartridge for applying pressure against said plunger for moving said sliding element in said second casing.

19. The invention defined in claim 18 and said connecting means between said pressure applying means and said sliding member including a trigger and firing device on said kit for firing said cartridge, and a trigger line between the trigger and firing device and said sliding member to trigger said trigger firing device whenever said sliding member is moved beyond said predetermined distance.

20. The invention defined in claim 19 and means in said cartridge to delay the action of said explosive charge for a predetermined period after the operation of said trigger and firing device.
